UNITED STATES PATENT OFFICE

BENNIE SCHWARTZ, OF BROOKLYN, NEW YORK

SHADE ROLLER

Application filed May 25, 1932. Serial No. 613,386.

The invention is a shade roller in which means is provided for preventing the complete unwinding of the spring, which is caused by the shade continuing to rotate after it reaches the top, when the shade is unintentionally released and rapidly rolls up to the top of the window.

The object of the invention is to provide a shade roller in which means is provided for preventing the spring unwinding beyond the point at which it has sufficient tension to roll the shade.

Another object of the invention is to provide in a shade roller means for limiting the rotating movement of the spring core when the spring is unwinding.

Another object of the invention is to provide a shade roller in which the roller may only rotate to roll up the shade exactly the same number of turns it has rotated to roll the shade down.

Another object of the invention is to provide a travelling member in a shade roller which will engage a stop to prevent the spring core and roller unwinding beyond a predetermined distance.

A further object of the invention is to provide a device that may be installed upon the interior of a shade roller for preventing the roller completely unwinding which may be installed in any type of shade roller or in a spring roller that may be used for any other purpose.

And a still further object of the invention is to provide means for limiting the movement of a shade roller to prevent the complete unwinding of the spring, which is of a simple and economical construction.

With these ends in view the invention embodies a shade roller having a spring with a threaded rod inside of the spring and a nut on the threaded rod with means for preventing the nut rotating with the rod, and means at the ends for limiting the travel of the nut on the rod.

Other features and advantages of the invention will appear from the following description taken in connection with the drawing, wherein:

Figure 1 is a view showing a shade roller with the device incorporated therein.

Figure 2 is a view showing a portion of a shade roller with part broken away showing the spring.

Figure 3 is a cross section thru the spring with the roller omitted, taken on line 3-3 of Figure 2.

Figure 4 is a longitudinal section thru the end of the roller with the wood portion of the roller indicated in dotted lines.

Figure 5 is an end view of the roller.

Figure 6 is a section similar to that shown in Figure 3 in which a nut of an alternate design is shown.

Figure 7 is a similar section showing alternate means for preventing the nut rotating.

In the drawing the device is shown as it would be made wherein numeral 1 indicates a shade roller, numeral 2 a shade roller spring, and numeral 3 a threaded rod forming the core of the spring.

It will be understood that a shade roller of any type or design may be used and the roller may be made of wood, metal, or of any material. The spring roller may also be used for window shades, awnings, blinds, curtains, or for any other purpose. In the design shown the roller is made of wood and is provided with a cylindrical opening 4 in one end in which the spring 2 is mounted as shown.

At the end of the roller is a cup-shaped disc 5 and it will be noted that one end of the spring 2 is attached to a projection 6 on the disc 5 and the opposite end of the spring is held in a slot or opening 7 in the rod 3. It will be understood that the spring may also be held to the end of the rod 3 by any other means. The disc 5 may be attached to the end of the roller 1 by points 8, or held thereto by any other means.

It will be noted that the usual flat shank or pintle, as indicated by the numeral 9, is provided at the end of the rod 3 and this may be made integral with the rod or attached to it in any manner. With the shank 9 held in a socket at the edge of a window frame, or the like, a shade 10 on the roller may be drawn downward and as it is drawn down-

ward it will wind the spring so that when the shade is released the spring will draw the shade upward. The shade may be held at any position by the usual dogs 11 operating in recesses 12 in a disc 13 at the end of the shank 9.

In an ordinary window shade the rod 3 is not threaded and when the shade 10 is released it is free to run up to the top of the window and very often the spring continues to unwind so that the tension on the spring is released and the spring is not sufficient to raise the shade all the way to the top of the window. In order to prevent this the rod 3 is threaded and a threaded nut 14 placed on the rod and held in a sleeve 15 so that when the shade is pulled downward the nut 14 will travel on the rod 3 and when the shade is released and raised the nut 14 will travel back to the starting position. When installing the device it is so arranged that the nut 14 may rest against the end of a bearing 16 at one end of the rod 3, or with opposite hand threads the nut 14 may rest against an end of a bearing 17 at the opposite end of the sleeve. With the nut in this position and the spring slightly wound or wound sufficiently to produce tension to raise the shade, which is known as the adjusted tension, the shade may be drawn downward and as it is drawn downward the nut 14 will travel on the threads on the rod 3 away from the bearing, the end of which forms the stop, and when the shade is raised the nut 15 will travel back the same distance it moved when the shade was drawn downward, thereby permitting the rod 3 to make exactly the same number of turns as the shade is raised, that it made in the opposite direction, when the shade was lowered, and as the nut will strike the end of a bearing it will prevent the rod turning further, or the roller running free, or the shade continuing to rotate on the roller after it has reached the top. It will be noted that whenever the shade is released it can only unwind until the end of the nut engages one of the limiting stops or ends of the bearings which will therefore make it possible to maintain the adjusted tension in the spring at all times and also make it impossible for the spring to completely unwind. The roller will otherwise operate in a manner similar to that of the ordinary shade roller.

It will be understood that the nut 14 may be of any shape or design and the sleeve 15 may also be of any shape so that it will correspond with the nut and prevent the nut rotating as it travels on the rod 3. In the design shown in Figure 6 the nut, which is indicated by the numeral 18, and also the sleeve, which is indicated by the numeral 19, are both made of an elliptical shape, however, it is understood that they may be made 65 of any other shape. In the design shown

in Figure 7 the nut, which is indicated by the numeral 20, is made round and is slidably mounted on rods 21. It will be understood that any number of rods may be used and they may be mounted in any manner desired.

It will be noted that the sleeve 15 is provided with extensions 22, which may be made integral therewith or formed in separate pieces and attached to the sleeve in any manner desired, and these may be held in the disc 5, as shown at the points 23, in Figure 4. It will be understood, however, that this sleeve may be held to the disc in any other manner or may be attached to the roller in any manner as long as it is stationary with the disc. It will also be noted that the central part of the disc 5 is stamped inward forming the bearing 16 to hold the end of the rod 3 and it will be understood that this bearing may also be formed in any other manner, and at the opposite end of the rod where the rod is held in the bearing 17 of the sleeve 15 the rod is turned downward to the root of the threads thereby providing a smooth bearing, however it will be understood that this bearing may be formed in any other manner, and also that the bearing may be omitted.

It will be understood that other changes may be made in the construction without departing from the spirit of the invention. One of which changes may be in the use of any other means for mounting and holding the nut 14 or the travelling member in a shade roller, another may be in the use of other means for causing a nut or travelling member to move as the shade is pulled downward or as it is pulled upward, and still another change may be in the use of other means for limiting the movement of the said travelling member.

The construction will be readily understood from the foregoing description. In use the device may be provided as shown and installed in a shade, or other spring roller of any type or description and it will be noted that the shade may be pulled downward in the usual manner without any interference whatever from the travelling member 14, and also that the shade may be raised by the spring and as long as it operates in the same manner as the spring rollers now in use, this device will not interfere with the operation, however, when a shade is unintentionally released this device will come into action and prevent the spring unwinding beyond the adjusted tension, thereby eliminating the trouble and inconvenience of taking down the spring roller and rewinding the spring, and also eliminating the possibility of tearing the shade and breaking the spring as often happens.

Having thus fully described the invention what I claim as new and desire to secure by Letters Patent is:

1. In a shade roller, a spring, and a travelling member within said spring, and means limiting the movement of the travelling member to prevent complete unwinding of said spring.
- 5 2. In a shade roller, a spring, a threaded core in said spring, a nut on said threaded core, means causing the nut to rotate on the core, said nut and means causing the rotation thereof, positioned within said spring, and means limiting the movement of said nut to prevent complete unwinding of said spring.
- 10 3. In an attachment for shade rollers, a spring for winding said roller, and means within said spring preventing complete unwinding of said spring.
- 15 4. In an attachment for shade rollers, a spring adapted to be inserted in the end of the roller, a threaded core in said spring, a travelling member on said threaded core and within said spring, and rotatable means holding said travelling member causing its rotation on said core.
- 20 5. In an attachment for shade rollers, a spring adapted to be inserted in the end of the roller for rewinding the roller, and a travelling member inside of said spring to prevent complete unwinding thereof.
- 25 6. In an attachment for shade rollers, a spring for rewinding said roller, a travelling member inside of said spring, means causing said travelling member to move in one direction as a shade on the roller is drawn downward, and means preventing said travelling member moving beyond the starting point when the shade moves upward or travels in the opposite direction.

In testimony whereof I affix my signature.
BENNIE SCHWARTZ.
